US0D1070063S

(12) **United States Design Patent** (10) **Patent No.:** **US D1,070,063 S**
(45) **Date of Patent:** **** Apr. 8, 2025**

(54) **AIR CIRCULATOR**

(71) Applicant: **Iris Ohyama Inc.**, Sendai (JP)

(72) Inventor: **Shohei Tokoi**, Kakuda (JP)

(73) Assignee: **Iris Ohyama Inc.**, Sendai (JP)

(**) Term: **15 Years**

(21) Appl. No.: **29/812,304**

(22) Filed: **Oct. 20, 2021**

(30) **Foreign Application Priority Data**

Apr. 21, 2021 (JP) ..... 2021-008458 D

(51) **LOC (15) Cl.** **23-04**

(57) **CLAIM**

The ornamental design for an air circulator, as shown and described.

DESCRIPTION

FIG. 1 is a front, top and right-side perspective view of an air circulator showing my new design;

FIG. 2 is a front view thereof;

FIG. 3 is a rear view thereof;

FIG. 4 is a top view thereof;

FIG. 5 is a bottom view thereof;

FIG. 6 is a right-side view thereof; and,

FIG. 7 is a left-side view thereof.

The broken lines shown represent portions of the air circulator and form no part of the claimed design.

1 Claim, 7 Drawing Sheets
